UNITED STATES PATENT OFFICE

WALTER C. ELZE, OF FOREST HILLS, NEW YORK, ASSIGNOR TO HAUCK MANUFACTURING COMPANY, OF BROOKLYN, NEW YORK, A CORPORATION OF NEW YORK

BURNER APPARATUS

Application filed November 18, 1927. Serial No. 234,109.

The invention relates to burner apparatus designed to utilize a liquid fuel and adapted more particularly to the removal of snow and ice from switches; the destruction of vegetation, as weeds, and extermination of insect pests and their larvae and eggs; also, as thawing outfits for hoppers of freight cars and for dumping mechanism, and in terminal yards for interlocking plates, cranks, throw rods, etc.

It has for its object to provide a one-man outfit of this type which may conveniently be manipulated, as well as being readily transportable. A further object of the invention resides in the provision of means whereby a flat fan-shaped flame will be delivered from the burner and maintained for an appreciable distance in the burning zone; and be readily directed to the surface over which the burner apparatus is moved for destruction of the matter in its path. The invention contemplates, also, a novel construction whereby the apparatus may readily be guided over and follow the contour of a surface in the operation of applying the flame. Further features of the invention reside in the provision of a windshield which is conveniently removable to admit of access to the nozzle member of the burner apparatus so that said member may readily be replaced or repaired, if necessary. A still further object of the invention resides in the mounting of portions of the burner apparatus to enable regulation of the length of flame to the desired degree when initially setting the burner.

In carrying out the invention, use is made of a sled member preferably rigidly secured to the fuel supply element, the latter terminating in an angularly disposed handle portion suitable for manually moving over the ground the burner apparatus carried on the said sled portion thereof. The fuel supplying member, furthermore, includes a pre-heating coil or like portion at the outer end of the burner apparatus suitable for preliminarily heating and gasifying the liquid fuel prior to its delivery to the nozzle, while the latter is also of novel construction to deliver the gas or vaporized fuel issuing therefrom

in a substantially flattened and fan-shaped form. The same is then received by a substantially elliptical throat member mounted within a corresponding surrounding casing within which partial combustion of the vaporized fuel occurs.

The nature of the invention, however, will best be understood when described in connection with the accompanying drawings, in which:-

Fig. 1 shows in side elevation the novel burner apparatus.

Fig. 2 is an enlarged front elevation thereof.

Fig. 3 is an enlarged plan view; and Fig. 4 is an enlarged side elevation, partly in longitudinal section and with portions broken away.

Fig. 5 is a detail fragmentary longitudinal section of the nozzle plug.

Referring to the drawings, 10 designates a suitable element constituted preferably by a portion of the fuel supply pipe and horizontally disposed, to which is attached, preferably rigidly, and positioned beneath the same, a sled or like member 11 adapted to rest on the ground or other surface 12 over which the burner apparatus is to be moved in applying it for the various purposes in view. The said sled member to this end may be provided with a pair of runners 13 and intermediate shell 14, the same affording an ignition receptacle, and both shell and runners being more or less rounded at the bottom to readily and smoothly move over surfaces of varying contour as met with in the application of the burner apparatus, the necessary power for effecting the movement of said apparatus over a surface being manually applied through a handle member 15 constituted by the upper portion of the pipe introducing the liquid fuel to the burner apparatus. This handle portion may be inclined at a suitable angle to conveniently push the entire apparatus along a surface. A control valve 16 is included in the fuel line as at the upper portion of said handle member which is connected, for example, through a hose connection 17 with a suitable source of fuel supply or tank therefor (not shown)

which may be carried on an operator's back or otherwise transported to follow the motion of the burner apparatus.

The latter comprises a casing 20, preferably of elliptical section, for enclosing a worm or like preheating device 21 which is an extension of the intermediate portion 10 through which the incoming fuel travels, said coil being located substantially at the outer end of the casing 20. Through a rearwardly directed pipe 22 from said coil, the heated and partly gasified fuel flows to the rear portion of said casing 20, pipe 22 terminating at an axially disposed nozzle member 23 which may consist of a plug screwed therein and having a plurality of apertures 24 horizontally disposed in a common plane, as indicated more particularly in Figs. 2 and 5 of the drawings. In order better to spread the issuing jets, a number of the apertures may be located therein at an angle to the longitudinal axis of the nozzle member, for example, the two apertures upon either side of the central one—all radiating from a common center and providing thereby a more or less flattened and fan-shaped jet. Said nozzle, moreover, discharges into an open-ended substantially elliptical throat member 25 positioned somewhat beyond the nozzle apertures 24 to assist in developing and maintaining a flat form of flame when the fuel issuing from the said apertures ignites, the said surrounding throat member communicating, also, at its rear portion freely with the atmosphere to permit air for the primary combustion of the fuel to be drawn inwardly by the issuing spray as well as by the subsequent combustion thereof in the casing. Moreover, the throat member is secured to the outermost casing 20 which latter in turn is adjustably carried on the fuel pipe portion 10 as through a sleeve 26, so that the entire assembly may be set along same and fixed in any desired position as by means of a set screw 27. Further air admission openings 28 are provided in the rear wall of the casing 20 as well as through the said casing at its peripheral portion immediately surrounding the throat member 25. By the hereinbefore described arrangement, ample air for supporting the combustion of the vaporized fuel will be afforded, the fuel as well being preliminarily heated to effect more efficient combustion in the resulting flame. The point of partial combustion thereof, occurring within casing 20, is more or less determined by the positions of the nozzle and throat members relatively to each other, the position of said throat member influencing also the length of the ultimate flame beyond the mouth of the burner apparatus. The said throat member is generally so positioned that the initial combustion zone will begin approximately at the innermost convolution of the preheating coil 21,

or at least not to any extent behind the same, so that most effective preheating will be attained and undue heating of the shell behind said coil obviated.

In regulating the flame, it is to be noted that it should initially be formed behind the outlet or mouth of the burner apparatus an extent sufficient to allow ample time for it to assume the flattened form; and it will be appreciated that the inward position at which the flame begins controls, also, the distance beyond the mouth of the burner apparatus to which the flame maintains its shape, and that both the throat member and outermost surrounding casing are effective in maintaining the desired flattened form thereof. This form has been found most effective in providing for a cutting action as well as burning; and by means of rocking the sled carrier, it is possible to direct effectively said flame toward the object to be destroyed.

To guard against the effect of a strong breeze or other disturbing atmospheric influences, it is preferred to equip the said burner apparatus along one side with a suitable shield 30 which may be secured adjacent the nozzle member. A means of convenient attachment is indicated in the drawings, the said shield 30 being removably fastened to a bracket 31 extending rearwardly from the shell 20 and being further secured by a rearwardly directed arm 32 terminating in a sleeve 33 slidable on the handle portion 15 and adapted to be rigidly secured thereto.

In starting the burner apparatus, oil-saturated waste may be placed in the interior of the shell 14 and ignited, the bottom of casing 20 being cut away or provided with an opening 34 to admit of access to the interior of the shell.

I claim:—

1. Flame projecting apparatus operating with liquid fuel, comprising a fuel supply pipe affording an inclined handle-constituting portion, an outer coiled portion terminating in an inner fuel delivery end, and an intermediate horizontal portion; a casing surrounding the coiled portion and the inner wall thereof being provided with an opening through which fuel is discharged into said casing, and the latter being provided also with a bottom opening; and a hollow sled member secured to the said intermediate portion beneath the bottom opening of said casing to receive igniting material and solely supporting the entire apparatus and enabling it to be moved, through application of force to said handle-constituting portion, freely over a surface and to be also tiltable thereby for directing the projected flame.

2. Flame projecting apparatus operating with liquid fuel, comprising a fuel supply pipe affording an inclined handle-constituting portion, an outer coiled portion terminating in an inner fuel delivery end, and an

intermediate horizontal portion; a casing surrounding the coiled portion and the inner wall thereof being provided with an opening through which fuel is discharged into said casing, and the latter being provided also with a bottom opening; a hollow sled member secured to the said intermediate portion beneath the bottom opening of said casing to receive igniting material and solely supporting the entire apparatus and enabling it to be moved, through application of force to said handle-constituting portion, freely over a surface and to be also tiltable thereby for directing the projected flame; and a shield disposed at one side of the apparatus between the inner end of the casing and the handle.

In testimony whereof I affix my signature.
WALTER C. ELZE.
